ABSTRACT OF THE DISCLOSURE

A hook and eye fastener intended primarily for articles of clothing has a hook plate and an eye plate each capable of being made from sheet material by simple shearing and forming operations. The eye plate has an opening and one or more outwardly shaped bridges across the opening. The hook plate has an opening which receives a bridge, with the hook projecting under the bridge, and a lip to snap against the bridge when the hook is fully inserted.

This invention relates to hook and eye fasteners which may be useful on various articles of clothing and in one embodiment it is especially advantageous in uniting lightweight straps such as in brassieres.

The flat plates may be secured to the ends of the straps or the like by heat sealing, stitching or other suitable means. They are easily united by an endwise movement with a final snap action to provide a fastener which is strong in tension and at the same time capable of being easily disengaged by a slight tilting and endwise movement. The overall thickness of the fastener when the plates are united, need be little if any greater than the combined thickness of the two pieces or sheets of flat material from which the hook and eye plates are made. The bridge of the eye plate is accommodated in the opening of the hook plate and the hook is similarly accommodated in the opening of the eye plate with the result that the fastener is comparatively smooth on both the inner and outer faces.

Various other objects and advantages of the invention will appear in the course of the following description.

In the accompanying drawings, I have shown for purposes of illustration two embodiments which the invention may assume in practice. In these drawings:

FIG. 1 is a plan view of an eye plate;

FIG. 2 is a plan view of a hook plate;

FIGS. 3 and 4 are longitudinally extending sectional views through the eye plate and hook plate respectively;

FIGS. 5 and 6 are plan and central longitudinal sectional views respectively of the two plates fastened together;

FIG. 7 illustrates in longitudinal section the action of the hook and eye plates when being united or separated;

FIG. 8 and 9 are plan views of a modified form of fastener showing the eye and hook plates respectively; and

FIGS. 10 and 11 are plan and central longitudinal sectional views respectively of the modified form of the fastener.

The eye plate shown in FIGS 1 and 3 is basically a flat piece 12 which can be stamped out of sheet material and the entire fastener is intended to be manufactured from a suitable plastic material. The hook plate is also a generally flat piece of sheet material 13. The invention is not particularly concerned with the manner in which the hook and eye plates may be attached to straps or other parts of a garment. In FIGS. 1 and 2, there is

2

indicated a strap receiving aperture 14 for the eye plate and a similar aperture 15 for the hook plate.

The engaging end of the eye plate has an opening 16 which may be of rectangular shape or the inner end portion 17 of the opening may be angular as seen in FIG. 1. A transversely extending portion of the sheet material is shaped outwardly of the plate 12 to make a bridge 18 extending transversely across the opening 16.

The hook plate at its engaging end has an opening 19 which is at least large enough to receive the bridge 18 of the eye plate. A hook 20 projects from the front transversely extending edge 21 of the opening 19 and is shaped to extend outwardly from the plane of the hook plate 13 and at least partially across the hook plate opening 19. The free end or lead portion of the hook 20 is spaced slightly from the flat plate 13 so that the hook may be inserted endwise under the bridge 18 of the eye plate. At the base of the hook there may be a shoulder 22 and when the hook is fully inserted as seen in FIGS. 5 and 6, the hook receiving edge 23 of the bridge 18 will come to rest against the shoulder 22.

In order to unite the parts, it is necessary only to put the hook and eye plates in overlapping relation with one being angled slightly relative to the other, and move the hook plate endwise so that the hook 20 slips under the bridge 18. When the bridge comes against the stop shoulder 22, the hook plate is drawn downwardly by the resilience of the hook as seen in FIG. 7 so that the edge along that side of the hook plate opening opposite the hook may snap against the adjacent transversely extending edge 23a of the bridge 18. The opening 19 is preferably shaped so as to provide a lip portion 24 somewhat narrower than the opening 19 so that it will be more readily snap over the bridge on the eye plate.

When the parts are thus engaged, they will be held snugly together so that the normal looseness in hook and eye fasteners is avoided. Furthermore, it will be observed that the bridge 18 fits nicely in the opening of the hook plate and the hook 20 does not project appreciably below the lower surface of the eye plate when the two parts are united. The entire fastener will, therefore, have an overall thickness not substantially greater than the combined thickness of the two flat plates 12 and 13.

The modification shown in FIGS. 8 to 11 inclusive, illustrates various differences in construction embodying, however, the same basic principles as the fastener already described. The eye plate 25 is rectangular and has holes 26 around its border and central holes 27 by which it may be sewn to a garment. There are two rather long openings 28 and 29 extending lengthwise of the plate 25 and three pairs of bridges 30, 31 and 32 extending across these openings. The hook plate 33 may also have sewing holes 34 for attaching it to a garment, and a pair of hooks 35 and 36 which may be engaged selectively with any one of the pairs of bridges on the eye plate 25.

Another variation is the provision of slots 37 at either side of each hook to increase the flexibility. It will also be observed that instead of a shoulder like that indicated at 22 in FIG. 4, the plate edge portions 38 on each side of the base of the hook will cooperate with the inner transverse edges of the bridge portions of the eye plate to serve as a stop as best seen in FIG. 10. The hook plate openings 39 and 40 also may be varied in shape by providing the curved edges 41 and 42 to make a flexible portion for snapping over the outer transverse edges of the bridges 30, 31 or 32. The operation of the modified form of fastener is substantially the same as that which has already been described with reference to FIGS. 1 to 7. In addition, of course, the feature of adjustability is provided since the hooks 35 and 36 may be engaged with any one of a plurality of pairs of bridges on the eye plate.

We claim:

1. A snap engaging hook and eye fastener comprising an eye plate and a hook plate adapted to be united in overlapping relation, each plate being formed from resilient sheet material, said eye plate having an opening, a transversely extending portion shaped outwardly of the eye plate to make a bridge across said opening, the bridge having an entrant edge, said hook plate having an opening adapted to receive said bridge, a hook projecting from one transversely extending edge of said hook plate opening, outwardly from the plane of said hook plate and at least partially across said hook plate opening, the lead portion of the hook being spaced from the hook plate a sufficient distance so that it may be inserted endwise under the entrant edge of the bridge, and cooperating means on said hook plate and bridge to limit such endwise insertion of the hook to a position where the edge along that side of the hook plate opening opposite the hook, may snap over the edge of said bridge opposite said entrant edge.

2. A fastener as defined in claim 1 wherein the eye plate opening extends a substantial distance in front of the entrant edge of the bridge to facilitate insertion and removal of the hook.

3. A fastener as defined in claim 1 wherein said bridge is shaped outwardly from the eye plate only enough so that it will lie approximately in the plane of said hook plate when the two plates are united.

4. A fastener as defined in claim 1 further characterized by a lip along that edge of the opening in said hook plate which is opposite to the hook, said lip being adapted to snap into edge-to-edge contact with said bridge to hold

said hook tightly against said bridge to minimize looseness when the plates are united.

5. A fastener as defined in claim 1 wherein the means to limit insertion of the hook comprises a shoulder at the base of the hook adapted to abut the entrant edge of the bridge.

10. A fastener as defined in claim 1 wherein said means to limit endwise insertion of the hook consists of plate edge portions on opposite sides of the hook, which edge portions abut the entrant edge of the bridge when the hook is fully inserted.

15. A fastener as defined in claim 1 wherein the hook and eye plates are adapted to be made from plastic material in sheet form, the fastener when the parts are united having an overall thickness not substantially greater than the combined thickness of the two sheets from which the plates are formed.
